UNITED STATES PATENT OFFICE.

SYLVESTER BARCUS, OF ETNA, OHIO.

SKID-ELEVATOR.

SPECIFICATION forming part of Letters Patent No. 298,933, dated May 20, 1884.

Application filed April 14, 1884. (No model.)

To all whom it may concern:

Be it known that I, SYLVESTER BARCUS, a citizen of the United States, residing at Etna, in the county of Licking and State of Ohio, have invented new and useful Improvements 5 in Skid-Elevators, of which the following is a specification.

My invention relates to improvements in portable elevators, in which a skid is provided with a platform, and means for drawing it up and letting it down the incline for loading wagons with boxes, barrels, and other articles of merchandise too heavy to be carried or lifted by hand, or for raising such articles 15 from a cellar or lowering them therein; and the object of my improvements is to provide a platform adapted for use in an inclined position upon the skid for boxes, sacks, &c., supplemented, when required, with an attachable horizontal platform adapted for elevating and lowering barrels, to render the device more complete, and to facilitate the removal or dumping of the article from the platform when raised.

25 Referring to the accompanying drawings, Figure 1 represents, in perspective, my improved elevating-skid with the sectional inclined platform; Fig. 2, a longitudinal section of the same, showing in dotted lines the upper section of the platform dropped out of the way over the upper end of the skid; Fig. 3, the elevating-skid with the horizontal supplemental platform applied; and Fig. 4, a longitudinal section of the same, showing the manner 30 of fastening the supplemental platform to the upper edge of the inclined platform. Fig. 35 shows the supplemental platform.

The skid is formed of parallel beams *a a*, connected together by cross-bars *b*, and beveled at their lower ends to rest upon the pavement, and at their upper ends to rest against the wagon or other place, when supported in an inclined position for use. On their inner sides the beams are provided with cleats or 40 ways *c*, below and parallel with their upper edges, upon which the platform moves and is confined. The platform is in two sections, *d e*, hinged together, so that the upper section, *e*, when raised its full height, will drop down 45 out of the way over the upper end of the skid or into the wagon, and thereby leave the sack or other article projecting over the upper end

of the lower section to give freedom for handling and taking it off and for dumping boxes. The lower section has a guard, *f*, upon which 55 the article rests when the inclined platform is used. The platform is raised by a cord, *g*, attached to its under side, and passing over a roller, *h*, at the upper end of the skid below the cleats, passes over and is attached to a 60 winding-roller, *i*, mounted on the skid near the middle of its length, and turned by a crank, *j*, applied to its end, which for that purpose projects at the side of the skid-beam. When raised in dumping position, the platform 65 is supported from falling down by a stop, *k*, pivoted to the upper edge of the skid, and turned so that the platform will rest against it. The inclined platform is used for elevating or lowering such articles as can be safely 70 supported against the guard; but for barrels I provide a supplemental horizontal platform, *l*, fastened by a bolt, *l'*, or otherwise to the upper end of the inclined platform, and supported in a horizontal position by an under projecting cross-piece, *m*, resting on the guard *f*, 75 where it joins the inclined platform. The supplemental platform is removably attached in any simple manner at its inner end, so that it cannot be tipped over, and its inner end is 80 beveled to rest upon the inclined platform, and its supporting-piece *m* is beveled at its lower edge to rest in the angle of the guard and platform. If desired, the inclined platform may be provided with angle-irons extending 85 beneath the ways to prevent the accidental displacement of the platform in loading. The platform may be provided with rolls, and the skid may be of any desired length and width. The upper end of the skid 90 is provided with the usual holding hook-irons. The lower cross-bar connecting the skid-beams forms the stop to hold the platform in place when lowered.

It will be understood that the upper section 95 of the hinged platform will be supported upon the ways until its hinged end reaches the ends of the ways, when it will fall and hang in position to be drawn up upon the ways as the platform is lowered, as shown by dotted 100 lines in Fig. 2, and that this dumping-section can be used with the supplemental platform to elevate articles with the barrel.

I claim—

1. The elevating-skid having a platform provided with an upper hinged section adapted, when raised, to fall out of the way over the end of the skid, substantially as described; 5 for the purpose specified.
2. The elevating-skid having an inclined platform supplemented with a removable horizontal platform, substantially as described, for the purpose specified.
- 10 3. The supplemental platform having one end beveled and a cross-piece on one side near its other end, combined with the inclined platform and means for fastening the supplemental platform to the upper edge of the inclined platform, substantially as described, for the purpose specified.
- 15 4. The inclined platform having an upper hinged section, combined with a supplemental horizontal platform adapted to be supported

upon and removably attached to the lower 20 section of the inclined platform, the skid, and means for elevating the platform, substantially as described.

5. The elevating-skid herein described, consisting of the skid, the inclined platform of 25 hinged sections, the attachable supplemental horizontal platform, the cord *g*, the roller *h*, the cranked winding-roller *i*, and the pivoted stop *k*, all constructed and arranged substantially as set forth.

In testimony whereof I have hereunto set my hand in the presence of two subscribing witnesses.

SYLVESTER BARCUS.
